OXYGEN DILUTER VALVE

Donald F. Diedrich, Temecula, and John H. Price, La Jolla, Calif., assignors to Hudson Oxygen Therapy Sales Company

Filed June 26, 1972, Ser. No. 266,483

Term of patent 14 years

Int. Cl. D23—04

U.S. Cl. D23—19

FIGURE 1

FIGURE 2

FIGURE 3

FIGURE 4

FIG. 1 is an enlarged perspective view of an oxygen diluter valve, showing our new design;

FIG. 2 is a top plan view thereof;

FIG. 3 is a cross-section taken on line 3—3 of FIG. 4; and

FIG. 4 is a front elevational view thereof.

We claim:

The ornamental design for an oxygen diluter valve, as shown.
